United States Patent

Des. 237,530
Patented Nov. 4, 1975

237,530

RING OR SIMILAR ARTICLE

Eugene A. Poulin, 85 Royal Oak Road,
New Britain, Conn. 06053

Continuation-in-part of abandoned design application Ser.
No. 344,470, Mar. 26, 1973. This application June 24,
1974, Ser. No. 482,085

Term of patent 14 years

Int. Cl. D11—01

U.S. Cl. D45—10 B

FIG.1

FIG.2

FIG.3

FIG.4

FIG. 1 is a front elevational view of a ring or similar article showing my new design;

FIG. 2 is a right side elevational view thereof;
FIG. 3 is a rear elevational view thereof; and

FIG. 4 is a top plan view thereof.

This is a continuation-in-part of design application Ser. No. 344,470, filed Mar. 26, 1973, and now abandoned.

I claim:

The ornamental design for a ring or similar article, as shown and described.
